ELECTRIC SWITCH

Wilhelm A. Streuer, Mount Prospect, and Edward J. Mastney, Berwyn, Ill., assignors to Oak Mfg. Co., a corporation of Illinois

Application June 3, 1952, Serial No. 291,398

3 Claims. (Cl. 200—6)

1

This invention relates to an electric switch, and more particularly to a panel mounted rotary switch with lever actuation. Rotary switches having a number of index positions are frequently desirable for panel mounting with lever or handle actuation rather than a knob. In such case, the rotary switch is so mounted that the axis of rotation of the rotor portion of the switch is parallel to the panel. An index mechanism for such switch is necessary in order to set the switch to any one of a number of predetermined definite positions. This invention provides a construction which is simple and effective and has an index mechanism which operates with minimum friction and wear.

In order that the invention may be understood, reference will now be made to the drawing wherein an exemplary embodiment of the invention is illustrated, it being understood, however, that some variations are permissible.

Referring, therefore, to the drawing:

Figure 1 is a side elevation of a switch embodying the present invention;

Figure 2 is a section on broken line 2—2 of Figure 1;

Figure 3 is an elevation similar to Figure 1 but showing the other side of the new switch;

Figure 4 is a view along line 4—4 of Figure 3;

Figures 5 and 6 are perspective details of portions of the switch.

The new switch comprises base 10 of sheet metal, such as steel, for example. Base 10 has panel mounting portion 11 with index side portion 12 and rotor support portion 13. Panel portion 11 has elongated slot 16 lengthwise thereof and mounting apertures 17 and 18 at the two ends thereof.

Index side portion 12 has supporting arms 20 and 21 and slotted index portion 22. Index portion 22 consists of a number of teeth 23 disposed on an arc and spaced from each other by slots, the index portion as a whole subtending an angle with reference to the center of rotation of the switch.

Riveted to support arms 20 and 21, at suitable apertures, is stator 26 of a rotary switch. The switch illustrated here is described in detail in Patents 2,186,949 and 950. Other rotary switches may be used. Stator 26 is of insulating material and has a series of stator contacts 27 mounted along the arc of a circle. Contacts 27 are carried by suitable eyelets 28 or if desired may be staked in position. Each stator contact 27 extends inwardly of the stator and has oppositely disposed jaws 30 as shown. The interior portion 55

2

of the stator 26 is cut-out to form a circular region within which there is rotatively disposed rotor 32.

Rotor 32 consists of one or more insulating discs snugly disposed within the stator cut-out. Rotor 32 has a series of apertures 33 disposed along the arc of a circle whose center is coincident with the center of the rotor. Rotor contacts 34 are attached to the rotor at these holes by the rivets. These rotor contacts are flat strips of metal whose plane is parallel to the plane of rotation of the rotor, the contacts being adapted to lie on the outer surfaces of the rotor disc and extend beyond the disc edges and overlie parts of the stator. By controlling the angular extend of the rotor contacts, their position, the radial dimensions thereof and the reach of the stator contacts, as well as the number and position of the stator contacts, a wide variety of switch combinations are possible. Inasmuch as the patents identified above fully describe the rotary type of switch used here, a further detailed description is not believed to be necessary.

It is evident that the center of the rotor disc 25 is the center of rotation of the entire switch. While the rotor disc in the particular switch section disclosed here is self-supporting, this is not essential to the invention. Pin 36 is provided, this pin passing through a centrally disposed aperture in the rotor disc. Pin 36 has reduced portion 37 passing through aperture 38 in rotor-supporting part 13 of the frame.

Disposed around reduced portion 37 of frame 36 and against the inside face of rotor-supporting portion 13 of the frame is spring steel member 40. Spring steel member 40 has ear 41 engaging notch 42 in rotor support frame part 13. This functions to lock the spring steel member against rotation. Spring steel member 40 has fan-shaped portion 43 with slotted cut-out 44 for flexibility. Fan-shaped portion 43 underlies index part 22 and has substantially the same angular extent as the index part.

Pin 36 has enlarged portion 46 against which spring portion 40 may rest. Disposed over enlarged pin part 46 is actuating lever part generally indicated by numeral 48. Lever part 48 has mounting portion 49 having an aperture through which enlarged pin portion 46 passes. Pin 36 has shoulder 50 for supporting the actuating portion against sideways movement away from spring part 40. It will be noted that pin 36 has end 51 turned over to lock the assembly in position.

Actuating lever portion 48 has wings 52 and

53 and has handle portion 54 extending outwardly from the body of the lever portion. Wings 52 and 53 extend symmetrically from opposite sides of the handle portion. Disposed in the body of actuating portion 48 and near the lever or handle part 54 is retainer part 56 into which ball 58 rests. Ball 58 is small enough so that it may play within retainer part 56. Retainer part 56 is thin enough or shallow enough, as seen from the side in Figure 2, so that ball 58 will project from both sides of the lever. One part of the ball bears against index spring portion 43. The other part of ball 58 presses against index portion 22. Teeth 23 and the spaces between the teeth are so designed that ball 58 will be retained in position. Thus the spring and ball assembly cooperate with the toothed index portion to provide an index action.

In order to transmit rotary motion from actuating part 48 to the rotor of the switch, finger 60 on the actuating part is provided. This finger extends from rotor-supporting portion 49 at one side thereof and has the end portion bent at right angles to the plane of the body of the lever. Finger 60 is long enough to engage slot 61 in rotor-actuating plate 62 riveted to the switch rotor disc. It is obvious that by controlling the angular position of switch actuating plate 62 with respect to the switch rotor that the desired number of switch positions may be selected and determined. Thus a flexible construction is provided which makes it possible to tailor a rotary switch to any desired switch action over the index positions provided.

By having the index ball free in the lever, there will be no sideways thrust of the lever body against the frame of the switch, thus increasing friction.

It is understood, of course, that handle portion 54 of the lever extends through slot 16 in the panel portion of the frame and that a suitable knob or finger-piece of molded material may be disposed over the end of the lever for ready handling. The entire mechanism may be mounted

by bolts passing through apertures 17 and 18. Thus a simple and free-acting index switch, having a number of index positions, is provided.

If desired, a number of switch sections may be provided instead of one as shown. In such case, finger 60 may engage all the switch sections or the pin may be non-circular where it passes through the rotor discs. Hence when finger 60 drives one disc, others will follow.

What is claimed is:

1. A rotary switch comprising a generally U-shaped base plate member, the bottom of the U being flat for panel mounting, one U arm having two spaced parts and the other U arm having an apertured end, a rotary switch having a stator and rotor, means for supporting the stator on the two spaced parts of said one U arm, a pin carried by said apertured end of the other U arm and normal thereto, said pin passing through said rotor, an actuating lever carried by said pin and having a handle portion extending through a slot in the flat panel mounting portion, a ball retainer carried by said lever, a ball in said retainer freely movable normal to the lever body plane, a spring arm carried by said pin and extending between the other U arm and lever body, said arm cooperating with said ball in all lever positions to press said ball toward the one U arm, index teeth formed in said one U arm so that said ball provides and index action, and means to couple said lever and rotor.

2. The switch according to claim 1, wherein the means to couple said rotor and lever comprises a slotted rotor plate secured to said rotor and a finger carried by said lever for engaging the slot in the rotor plate.

3. The switch according to claim 1, wherein said spring arm has a finger engaging a slot in the other U arm to lock the spring arm against rotation.
